(57) **CLAIM**

The ornamental design for a car seat pet mat, as shown and described.

DESCRIPTION

FIG. 1 is a front, right and top perspective view of a car seat pet mat, showing my new design.

FIG. 2 is a rear, left and bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof; and,

FIG. 9 is a top perspective view thereof in an unfolded state. The broken lines in the drawings illustrate portions of the car seat pet mat which form no part of the claimed design.

1 Claim, 9 Drawing Sheets
